UNITED STATES PATENT OFFICE

2,056,697

EXTENSION SUPPORTING ROLLER FOR
HEARSES

Henry Van Deest, Freeport, Ill., assignor to Henny Motor Company, Freeport, Ill., a corporation of Delaware

Application September 13, 1934, Serial No. 743,876

10 Claims. (Cl. 193—42)

This invention relates to hearses and has for its principal object the provision of a simple and practical form of extension roller to facilitate loading or unloading a casket from the rear end 5 of a hearse.

The latest designs of hearses have the body extended at the rear in what is known as a beaver-tail, and this has made it difficult to get the casket in or out. The extension roller of my 10 invention affords an outboard support and avoids laborious lifting. The roller is constructed to fold in and out of the way when not in use, so that it is easily accessible and presents a neat appearance.

15 The invention is illustrated in the accompanying drawing, in which—

Figure 1 is a horizontal section through the rear end of a hearse showing the extension roller in folded out of the way position;

20 Fig. 2 is a section on the line 2—2 of Figure 1; Fig. 3 is a similar section but showing the roller extended for use, and

Figs. 4 and 5 are fragmentary plan and rear views, respectively, of Fig. 3.

25 The same reference numerals are applied to corresponding parts throughout the views.

The hearse illustrated is of the type having the beaver-tail extension 6 on the rear end thereof terminating in front of the rear bumper 7. 8 is

30 the rear door closing the opening 9 through which the extension roller 10 of my invention is arranged to be projected to provide an outboard support beyond the last roller 11 on the floor 12 and over the extension 6, as indicated in Figs.

35 3—5. Obviously with such an additional supporting roller on which to rest the casket, the pall-bearers are relieved of the awkward lifting in loading and unloading the casket, the roller 10 being far enough out so that the end of the casket

40 can easily be placed thereon, or removed therefrom.

The device 10 consists of a roller 13 carried on an axle 14 supported at its ends on arms 15. The arms are fastened to the opposite ends of a torque 45 tube 16 and are carried on the ends of extension rods 17 at right angles thereto. The rods 17 are arranged to rest on the door sill 18 in the operative position of the roller device. (See Fig. 3.) The rods 17 are hinged, as at 19, on the reduced 50 ends 19 of plungers 20 slidable in guide tubes 21, which extend vertically downwardly from the sill 18. Caps 22 fit in the upper ends of the tubes 21 and are fastened suitably by screws 23 to the sill 18 and serve both as guides for the rods 17

55 to hold the same in the folded position of Fig. 2,

and as limiting stops for the plungers 20 when the rods 17 are in the unfolded extended position of Fig. 3. The floor of the hearse is formed to provide a recess just in front of the sill 18 to accommodate the projecting portion of the device 5 10 in its folded position, as indicated in Fig. 2, thus presenting a neat appearance. Rubber bumper rings 24 are provided on the inner ends of the arms 15 for engagement with the caps 22 when the rods 17 are slid down into the tubes 10 21 to the position shown in Fig. 2, whereby to silence the impact and also eliminate rattle so long as the device is in this position.

In operation, when the door 8 is opened, the extension roller 10 is moved to the operative position by simply raising it first to the limit of its upward movement, determined by the engagement of the plungers 20 with the caps 22, whereupon the roller is swung outwardly, hinging at 18, and brought to the position shown in Fig. 3, 20 in which the extension rods 17 rest on the sill 18. The casket can then be rolled out onto the extension roller 10, as appears in Fig. 3, the bottom of the casket being indicated by the line 25. When the extension roller is no longer required, 25 it is simply folded up and lowered to the position of Fig. 2, the bumper 24 cushioning the impact of the arms 15 with the caps 24 so that the operation is practically noiseless and there will be no rattling when the hearse is in motion. 30

It is believed the foregoing description conveys a good understanding of the objects and advantages of my invention. The appended claims have been drawn with a view to covering all legitimate modifications and adaptations. 35

I claim:

1. In a hearse having a rear door opening, and a beaver-tail extension therebeneath, means for supporting a casket at floor level over said extension comprising a cross-member, extension rods 40 arranged to reach from inside the hearse rearwardly through the door opening to support the cross-member in extended position, receptacles for said rods extending downwardly from the floor of the hearse, and plungers slidable in said receptacles and having the inner ends of said rods hingedly connected thereto.

2. In a hearse having a rear door opening provided with a sill and having a beaver-tail extension reaching downwardly and rearwardly from 50 the sill, means for supporting a casket substantially at the same level with the floor of the hearse over said extension comprising extension rods reciprocable up and down in guides provided in the floor of said hearse adjacent the sill, plungers 55

hingedly connected to the inner ends of said rods and serving to limit upward movement thereof in the guides, the said rods being arranged to be extended rearwardly from the plungers and rest 5 on the sill with the outer ends projecting over the beaver-tail, supporting arms carried on the outer ends of said rods and extending upwardly therefrom in the latter position of the rods, and a transverse casket support carried on the upper 10 ends of said arms.

3. In a hearse, an extensible casket support comprising a pair of parallel extension rods, upright guides in the floor of the hearse adjacent the door opening arranged to receive said rods in 15 their out of the way position, plungers hinged to the inner ends of said rods and reciprocable in said guides, means limiting upward movement of said plungers to prevent removal thereof from the guides and provide support for the rods in 20 their substantially horizontal extended position, supporting arms carried on the outer ends of said rods in angular relation thereto, and a transverse casket support mounted on the outer ends of said arms.

4. In a hearse, an extension support for caskets comprising, in combination, with a door sill, a pair of parallel extension rods, upright guides in the floor of the hearse adjacent the sill arranged to receive said rods in their out of the way 25 position, plungers hinged to the inner ends of said rods and reciprocable in said guides, means limiting upward movement of said plungers to prevent removal thereof from the guides and provide one point of support for each rod in their 30 substantially horizontal extended position, the rods both engaging the sill intermediate their ends for further support, supporting arms carried on the outer ends of said rods in angular relation thereto, and a transverse casket support mounted 35 on the outer ends of said arms.

5. In a hearse, an extensible casket support comprising a pair of parallel extension rods, upright guides in the floor of the hearse adjacent the door opening arranged to receive said rods in 40 their out of the way position, plungers reciprocable in said guides having reduced end portions hingedly connected to the inner ends of said rods, cap members in the upper ends of said guides permitting extension therethrough of the reduced 45 portions of said plungers and serving by abutment with the plungers to provide support for the rods in their substantially horizontal extended positions, supporting arms carried on the outer ends of said rods in angular relation thereto, and a transverse casket supporting roller mounted for 50 rotation on the outer ends of said arms.

6. A structure as set forth in claim 5 including cushioning means on the outer ends of said rods

for engagement with the cap members in the folded position of the extension support.

7. A hearse as set forth in claim 5 wherein the floor is formed with a recess adjacent the door opening to accommodate the supporting arms 5 and roller in the folded position of the device.

8. In a hearse, an extensible casket support comprising a pair of parallel extension rods, downwardly extending guides in the floor of the hearse adjacent the door opening arranged to receive 10 said rods in their out of the way inoperative position, plungers hinged to the inner ends of said rods and reciprocable in said guides, means limiting upward movement of said plungers to prevent removal thereof from the guides and provide 15 support for the rods in their operative position extending rearwardly from the hearse, and a transverse casket support carried on the outer ends of said rods.

9. In a hearse, an extension support for caskets comprising, in combination, with a door sill, a pair of parallel extension rods, downwardly extending guides in the floor of the hearse adjacent the sill arranged to receive said rods in their out of the way inoperative position, plungers 25 hinged to the inner ends of said rods and reciprocable in said guides, means limiting upward movement of said plungers to prevent removal thereof from the guides and provide one point of support for each rod in their operative position 30 extending rearwardly from the hearse, the rods both engaging the sill intermediate their ends for further support, and a transverse casket support carried on the outer ends of said rods.

10. In a hearse having a rear door opening, 35 and a door therefor, the combination with a door sill, and a floor on a higher elevation than the sill and terminating in inwardly spaced relation to the door whereby to provide a recess therebetween for an extensible casket support in its retracted inoperative position, an extensible casket support in said recess comprising a pair of laterally spaced extension rods extensible substantially horizontally from the hearse over the sill, upright guides in said hearse extending downwardly relative to the sill and adapted to receive 40 said rods in retracted inoperative position, each of said rods having a transverse portion on the outer end thereof which in the latter position of said rods is disposed substantially horizontally in 45 the recess behind the adjacent end of the floor, and casket supporting means carried on the outer ends of said transverse portions, which in the extended operative position of said rods is disposed 50 in substantially the same horizontal plane with the floor but in rearwardly spaced relation thereto outside the hearse.

HENRY VAN DEEST.
